NEW JERSEY

AIR RELIEF VALVE FOR HEATING SYSTEMS

Application filed January 14, 1930. Serial No. 420,685.

This invention relates to air relief valves for radiators of heating systems and consists of an improved design and structural arrangement adapted for more effectively relieving the system of entrapped air than the devices as heretofore used for the purpose, thereby to insure the maximum heating efficiency.

In the preferred embodiment of the features of the present invention there is employed a heat actuated valve member operative to seal the device or air passage automatically upon the displacement of the air by the heating medium and associated therewith there is provided an air check or relief valve in an arrangement yielding to internal pressures within the valve device and operative to seal the air passage against the intake of air whereby upon recession of the heating medium a vacuous condition will be established contributing to an improved circulation of the heating medium as will be readily understood. Further desirable features of the improved device consists of an improved design of bellows type heat actuated valve offering enlarged areas to the action of the heating medium to be quickly responsive thereto; the provision of a body of porous material through which the exhaust vapors are passed and operative to filter out and condense the water or liquid content and further in the arrangement of a deflecting surface associated with the intake opening to provide for more effective separation of the water from the steam or vapor and the return of the former to the heating system.

The foregoing and other improved features and advantages of the present invention will be more fully understood by reference to the accompanying drawings wherein like reference characters are applied to the corresponding parts in the several views.

In the drawings:

Fig. 1 is a central, vertical, sectional view of the air relief valve embodying the features of the present invention.

Fig. 2 is a horizontal, sectional view thereof taken on line 2—2 of Fig. 1.

Fig. 3 is a similar view taken on line 3—3 of Fig. 1.

Fig. 4 is a partial, vertical sectional view of the upper portion of the valve showing a desirable modification of the air check valve.

In the approved structural arrangement of the present invention as here shown, the air relief valve comprises a tubular casing or shell 1 having a tubular stem portion 2 thereon, the latter being externally threaded at 3 for attachment to the radiator of a steam or other heating system. The circular side wall of the shell 1 is internally threaded at 5 upwardly from its bottom open end portion and has its upper end portion formed with an upper horizontal wall 6 centrally provided with a venting passage 7 communicating with an upper outlet chamber formed within a hollow cap member 8 fitted upon a shoulder or annular extension 9 of the wall 6. The cap is provided with outlet openings 10 in its side wall portion.

For checking the outward flow or venting of the relief valve device, a valve member is provided in an arrangement to be responsive to the heat of the heating system, such as steam, and as here shown this outflow valve 75 consists of an expansible metal bellows 14 secured by means of a base flange 15 to a supporting member 16 formed with a lower flange portion threaded to engage the internal thread 5 of the casing member and formed with an inner chamber forming portion 18 extending upwardly within the bellows to provide an enlarged heat radiating surface. To the upper flange 19 of the bellows there is fitted an upper closing disc 20 having a central valve extension or pin 21 axially aligned with the venting passage 7; the latter being formed at its upper end with a reduced and tapered portion forming a valve seat for the tapered or conical upper end of the pin 21. 90 The chamber formed by the bellows 14 in conjunction with the closed wall of member 18 and the disc 20 is filled with a suitable expansible liquid, as for instance alcohol. As a result, upon heating of the liquid, the expansion will operate to raise the disc 19 and its valve pin 21 thereby to close the venting passage 7. The lower flange of the supporting member 16, as shown, is provided with openings or passages 22 communicating with 100

100

the interior of the casing therebelow and the chamber formed to surround the bellows thereby forming a by-pass for the escape of the air through the venting passage 7 under 5 the action of the internal pressures of the heating system until checked by the expandable valve as described, under the influence of the heating medium.

As will be readily understood, the automatically operating expandable valve will 10 maintain the valve closed throughout the period of the circulation of the heating medium. Upon cooling of the system, considered with relation to the structure insofar as described, 15 a vacuous condition would be established in the radiator and valve device and with the cooling of the expandable valve arrangement and resulting opening of the valve 21, the action would be to suck in air through the 20 venting passage. In accordance with a further feature of the present invention this action, under the conditions referred to, is prevented by the provision of an outwardly yielding valve, or air check, positioned at the 25 upper portion of the device and arranged to close the outer end of the venting passage 7 in a positive manner against the intake of air and to be yieldable to the internal pressures to allow for the air elimination.

30 The structural means for this purpose, as shown, comprises a compressible rubber, teat type valve member 25 having a self closing outlet opening 26 and secured in position to cover the venting passage 7 by being fitted 35 over a retaining flange 27 of a central boss portion of the wall portion 6 of the casing.

To further contribute to the effectiveness of the device, the space or chamber underlying the expandable valve is filled with a suitable porous material, as shown at 30, for instance metallic chips or shavings of non-corrosive metal such as bronze, brass or chrome-steel. As in the instance of steam heating the porous material functions to filter out the 45 water content with a condensing action to separate the water while allowing the upward passage of the air therethrough.

The bottom of the casing, as shown, is closed by a bottom wall member or disc 32 having 50 threaded engagement with the casing and formed, in accordance with the present invention, with a crowned or conical upper surface adapted to deflect upwardly the steam entering through the stem portion 2 and to provide 55 a marginal depression or groove for the collection of the water and to facilitate the return thereof to the system.

In the operation of our improved air relief valve, the entrapped air will be initially expelled through the venting passage 7 to escape through the outlet openings 10 under the action of rising pressures of the heating system which, as will be readily understood, opens the teat or outwardly valve 25. Upon 60 proper circulation of the heating medium, the

70 thermal actuated valve 21 will automatically close the venting passage to check further discharge therefrom and this condition will be maintained throughout the period of proper circulation of the heating medium. Upon subsequent drop in heating pressures the air check valve 25 will be operative to effectively seal the device against the intake of air and accordingly a vacuous condition within the 75 radiator will be established upon the drop in pressure and operative to quickly reestablish the circulation of the heating medium with resulting high heating efficiency.

75 While we have shown and described an approved embodiment of the features of the present invention, it will be understood that varied modifications may be made therein without departing from the invention as defined in the appended claims.

80 As illustrative thereof, we have shown in Fig. 4, a desirable modified construction of the air check valve arrangement, which as shown, comprises a valve cap and guide member 85 35 having threaded engagement with a wall extension 36 of the casing, is provided with air escape passages 37 and a central guide bore 38. Fitted within the lower end of the 90 guide bore is the pin 39 of a vertically operating valve 40 arranged to engage a perforated washer 41 surrounding the upper end of the 95 venting passage 7. The valve member, as shown, is of inverted cup formation providing an enlarged pressure area and is normally held against the seat or washer 41 by means of a light coil spring 42 retained under compression between the guide member and the upper surface of the valve member 40. Adjustment of the spring pressure may be effected by the thread adjustment of the guide member as will be readily understood.

100 Having described our invention, we claim:

1. An air relief valve device for radiators of heating systems comprising a suitable casing provided with an intake opening and a venting passage, a thermal responsive valve 105 adapted for automatically closing the venting passage consisting of a supporting member within the casing, an expandable bellows carried by the supporting member and provided with a valve positioned to close the 110 venting passage, said supporting member being formed with a by-pass opening for the passage of the fluid medium to the venting passage and having a chamber forming portion extending within the bellows and open 115 to receive the heating medium to provide an enlarged heat radiating surface and an expandable fluid contained within the chamber formed by the bellows and the supporting member; substantially as described.

120 2. An air relief valve device for radiators of heating systems comprising a suitable casing provided with an intake opening and a venting passage, a thermal responsive valve 125 adapted for automatically closing the vent- 130

ing passage, an air check valve operatively associated with the venting passage to be yieldable under venting pressure and to seal said passage to intake of air and a body of 5 porous material interposed between the thermal responsive valve and the intake opening, substantially as described.

3. An air relief valve device for radiators of heating systems comprising a suitable casing 10 provided with an intake opening and a venting passage, a thermal responsive valve adapted for automatically closing the venting passage and a body of porous metallic packing interposed between the intake opening 15 and the valve operative to condense the water content of the vapor passed therethrough.

4. An air relief valve device for radiators of heating systems comprising a suitable casing 20 provided with an intake opening and a venting passage, a thermal responsive valve adapted for automatically closing the venting passage and a body of porous metallic packing interposed between the intake opening 25 and the valve for condensing of the water content of the vapor and a member positioned adjacent the intake opening and formed with a conical deflecting surface positioned to deflect the vapors upwardly through the casing.

30 5. An air relief valve device for radiators of heating systems comprising a suitable casing provided with an intake opening and a venting passage, a thermal responsive valve adapted for automatically closing the venting 35 passage, a compressible rubber seat valve secured at the outer end of the venting passage and adapted to allow free venting of the vapor and to seal against air intake, a body of porous metallic material interposed be- 40 tween the intake opening and the thermal operating valve for condensing the water content of the vapor and a bottom wall member for the casing having a conical upper surface positioned for upwardly deflecting the 45 vapor entering the intake opening, substantially as described.

Signed at Brooklyn, in the county of Kings, city and State of New York this 6th day of January A. D. 1930.

50 SVEN A. JOHNSON.
FRANK C. RISSELT.
